UNITED STATES PATENT OFFICE

ALONZO STRINGHAM, OF NATIONAL MILITARY HOME, KANSAS

SPECTACLE CASE

Application filed July 24, 1928. Serial No. 295,024.

This invention relates to a spectacle case, and it is an object of the invention to provide a device of this kind provided with means whereby a comb may be carried within the case with the same facility as spectacles and wherein the case is of a type having only an end open, together with means for closing said open end.

Another object of the invention is to provide a case of this kind constructed in a manner wherein the spectacles or comb within the case may be readily taken therefrom without the necessity of withdrawing the case from the pocket in which it may be placed.

An additional object of the invention is to provide a case of this kind provided with a clasp for effectively securing or holding the case within a vest pocket or the like or to the waist band of trousers and wherein said clasp is secured to the case in a manner to permit the clasp to be swung away from the case when it is desired to remove the same and thus freeing the cloth of the garment of the wear to which it would otherwise be subjected. This is equally true in connection with the applying of the case within a pocket or to a waist band.

The invention consists in the details of construction and in the combination and arrangement of the several parts of my improved spectacle case whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be better understood, I will now proceed to describe the same with reference to the accompanying drawing, wherein:

Figure 1 is a view in side elevation of a case constructed in accordance with an embodiment of my invention;

Figure 2 is a vertical sectional view taken through the case as herein disclosed;

Figure 3 is a detailed sectional view taken substantially on the line 3—3 of Figure 1;

Figure 4 is a transverse sectional view

taken substantially on the line 4—4 of Figure 1.

As herein disclosed, my improved case comprises a body B of desired configuration and dimensions and which has its walls formed of metal, hard rubber or other preferred material. As is particularly illustrated in Figure 1, it is to be noted that the body B is substantially closed except at one end and which open end is adapted to be closed by a cap or lid L. This cap or lid L at one end portion is hingedly connected, as at 1, to a side wall 2 of the body B immediately adjacent to the open end of the case and said wall 2 and the hinged portion of the cap or lid L have associated therewith a spring 3 which serves, upon release of the holding latch 4, to automatically swing the lid or cap L into fully open position so that ready access may be had to the spectacles or comb placed within the body B.

The outer wall 5 of the body B is provided along its inner face and substantially its transverse center with a sheath or housing 6 extending from end to end of the body B and which coacts with the wall 5 to provide a compartment 7 of such dimensions to readily permit the insertion therein through the open end of the body B of a comb C. The sheath or housing 6 is of such size to offer no hindrance or obstruction to the ready insertion of the spectacles within the body B when desired.

The bottom wall 8 of the body B is provided with a central opening 9 to permit the ready release of such foreign matter which may be collected from time to time within the body B.

The side wall 2' of the body B closely adjacent to the open end of the body is provided with an inwardly disposed boxing 10 and said wall 2' and the opposed wall 11 of the boxing 10 provide a mounting for a shaft 12 disposed through the boxing 10 and extending exteriorly of the body B through the side wall 2'. This extended portion of the shaft 12 carries a milled head 13 whereby the shaft 12 may be manually operated when desired. The inner portion of the side wall 2' of the body B is provided with a longitudi-

nally disposed slot 14 affording communication within the boxing 10 and disposed through the slot 14 is an end portion of a clasp arm 15. The inserted end of this arm 15 is freely mounted upon the shaft 12 and is disposed in the path of travel of an angular extension 16 carried by a rock arm 17 movable with the shaft 12. The extended portion of the clasp arm 15 is disposed downwardly and inwardly with respect to the body B and closely conforms to the adjacent surface thereof.

The extended portion of the arm 15 is constantly urged toward the adjacent wall 5' of the body B through the medium of the coil spring 18 encircling the shaft 12 and having one end portion operatively engaged with the clasp arm 15 and its opposite end portion suitably anchored so that when the clasp arm 15 is moved away from the wall 5' of the body B the spring 18 will be placed under further tension, thus assuring return automatically toward the wall 5' of the body B and to assure the outer free end portion of the clasp arm 15 having requisite contact with the wall of a pocket or with the waist band of a trouser for effectively holding the case thereto.

When it is desired to remove the case the head 13 is turned by the person in a direction to rotate the shaft 12 to bring the angular extension 16 of the rock arm 17 in proper contact with the pivoted end portion of the clasp arm 15 to swing the outer portion of this arm 15 away from the wall 5' of the body B. This operation is also preferably preferred in applying the case to a pocket or waist band.

By having the clasp arm mounted and disposed as herein described and illustrated, said arm will hold the case to the wall of a pocket, such as a vest pocket, in a manner to relieve the same from undue strain and to prevent said pocket from assuming a sag appearance. In other words, the form of clasp arm as herein set forth does not affect the dressy appearance of the garment to which the case may be attached.

From the foregoing description it is thought to be obvious that a spectacle case constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as herein-after claimed.

I claim:—

1. A spectacle case comprising a body hav-

ing a slot in a wall thereof adjacent to a side thereof, a clasp arm having an end portion extending within the body through the slot, a shaft supported by a wall of the body and extending therein, the inserted end of the clasp arm being freely mounted on the shaft, said shaft being provided with means exteriorly of the casing for rotating the same, means for constantly urging the outer portion of the clasp arm toward the body, and a rock arm carried by the shaft, said rock arm engaging the clasp arm upon rotation of the shaft in one direction to move the clasp arm away from the body.

2. A spectacle case comprising a body having a slot in a wall thereof adjacent to a side thereof, a clasp arm having an end portion extending within the body through the slot, a shaft supported by a wall of the body and extending therein, the inserted end of the clasp arm being freely mounted on the shaft, said shaft being provided with means exteriorly of the casing for rotating the same, means for constantly urging the outer portion of the clasp arm toward the body, a rock arm carried by the shaft, said rock arm engaging the clasp arm upon rotation of the shaft in one direction to move the clasp arm away from the body, and a boxing within the body for enclosing the shaft, rock arm and adjacent portion of the clasp arm.

In testimony whereof I hereunto affix my signature.

ALONZO STRINGHAM.
